UNITED STATES PATENT OFFICE

2,535,761

CIGARETTE CASE

Stephen S. Szymanski, Holyoke, Mass.

Application September 13, 1946, Serial No. 696,841

2 Claims. (Cl. 206—41.2)

1

This invention relates to new and useful improvements and structural refinements in cigarette cases, and the principal object of the invention is to provide a device of the character herein described, such as may be conveniently and effectively employed as a dispensing cigarette container.

A further object of the invention is to provide a cigarette case into which the cigarettes may be readily inserted in package form, and from which they may be individually removed.

Another object of the invention is to provide a cigarette case in which the contents may be preserved in a fresh and unmutilated condition.

An additional object of the invention is to provide a cigarette case which is simple in construction and operation, and which will not easily become damaged.

A still further object of the invention is to provide a cigarette case which is pleasing in appearance and which will readily lend itself to economical manufacture.

With the above more important objects in view and such other objects as may become apparent as this specification proceeds, the invention consists essentially of the construction and arrangement of parts as shown in the accompanying drawings in which:

Figure 1 is a side elevation of the invention,

Figure 2 is an edge view thereof,

Figure 3 is a top plan view of the same,

Figure 4 is a cross-sectional view, taken substantially in the plane of the line 4—4 in Figure 3,

Figure 5 is a cross-sectional view of one of the receptacle sections used in the invention,

Figure 6 is a cross-sectional view, taken substantially in the plane of the line 6—6 in Figure 3,

Figure 7 is a perspective view of a pusher plate used in the invention, and

Figure 8 is a perspective view of a latch used in the same.

Like characters of reference are used to designate like parts in the specification and throughout the several views.

Referring now to the accompanying drawings in detail, the invention consists of a cigarette case designated generally by the reference character 10, the same embodying in its construction a pair of complementary sections 11, 12, separably connected together in a telescoped relationship and forming a receptacle 13.

A spring pressed pusher plate designated generally by the reference character 14 is hingedly secured in the section 11, the plate assembly 14 consisting of a length of resilient, wire-like rod

2

15 forming a substantially rectangular frame as is best shown in Figure 7, and having its end portions coiled to provide a pair of bearings 16. A hinge pin 17 passes through these bearings and is secured in the sides of the receptacle section 11, whereby the pusher plate 14 is hingedly mounted in the section, as aforesaid. It will be noted that the extremities 18 of the rod 15 are out-turned somewhat, so as to engage the adjacent wall of the section 11. In this manner, the pusher plate 14 will be urged in the direction of the arrow 19.

It will be also noted that the rectangular frame defined by the rod 15 is partially filled by a sheet 15 of material 20, which, if desired, may extend over the entire area of the frame.

A corner portion 21 of the section 11 is separated from the main body of the section and is hingedly connected thereto as at 22. The separation of the corner portion 21 forms a dispensing opening in the section 11, for which the portion 21, in effect, constitutes a cover designated by the same reference character. A suitable spring 23 is provided in the section 11 for normally urging the cover 21 into its open position as indicated by the phantom lines 24. Means are also provided for normally retaining the cover in its closed position, the same being designated by the general reference character 25.

30 The means 25 consists of a latch 26, assuming a substantially L-shaped configuration and having the relatively long arm thereof slidably positioned in a bearing 27, while its relatively short arm projects outwardly from the section 11 through a suitable slot 28. The projecting end portion of the latch 26 carries a manipulating knob 29 and it will be noted that the aforementioned bearing 27 is provided on the inner surface of the section 11, adjacent the cover 21.

35 The free extremity of the long arm of the latch 26 is removably engageable with a further bearing 30 secured to the inner surface of the cover 21.

40 The invention is placed in use, a package of cigarettes 32 is inserted into the receptacle 13 by simply separating the sections 11, 12. The upper portion of the package should then be removed and the pusher plate 14 inserted into the package, as is best shown in Figure 4. It will be observed that the pusher plate will urge the cigarettes 32 in the direction of the cover 21.

45 The cigarettes may be individually dispensed from the case by simply disengaging the latch 26 from the bearing 30, so as to allow the cover 50 21 to assume its open position (24) under the

resiliency of the spring 23. The cigarettes may, of course, be then removed individually through the uncovered dispensing opening.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A cigarette case comprising upper and lower telescoped sections, said upper section having first and second corners, said first corner having a dispensing opening therein, a pivot pin carried by the upper section and disposed at the second corner, a substantially U-shaped resilient, wire frame member having spaced leg portions, a sheet of material extending between and partially filling the space between the leg portions of said wire frame member, coils on the leg portions of said wire frame member receiving said pivot pin, and arms projecting from the coils and

yieldingly bearing against the inner surface of the upper section to urge the wire frame member toward the dispensing opening.

2. The combination of claim 1 and a closure for the dispensing opening, means pivotally securing the closure to the upper section, and a latch for holding the closure in its closed position.

STEPHEN S. SZYMANSKI.
